MONROE B. FOOTE, OF NORTHAMPTON, MASSACHUSETTS, ASSIGNOR
TO HIMSELF, WILLIAM M. GAYLORD, AND E. N. FOOTE.

Letters Patent No. 89,753, dated May 4, 1869.

IMPROVEMENT IN DOOR-LOCKS.

The Schedule referred to in these Letters Patent and making part of the same.

To all persons to whom these presents may come:

Be it known that I, MONROE B. FOOTE, of Northampton, in the county of Hampshire, and State of Massachusetts, have invented a new and useful Improvement in Mortise-Locks for Doors; and I do hereby declare the same to be fully described in the following specification, and represented in the accompanying drawings, of which—

Figure 1 exhibits a view of my improved lock as it appears with the cap removed from the rest of its case.

Figure 2 is an inner side view of such cap.

Figure 3 is a transverse section of the lock.

Figure 4 is a side view of its key.

The body of the case is cylindrical, the cap, shown in fig. 2, and also in fig. 3, at *b*, constituting part of such body.

This cylindrical body projects from a plate, *c*, which, when the lock is let into a door, is to be fastened to the door by screws.

The case contains a slotted bolt, *B*, it having a rectangular slot made through it, as shown at *d*.

Projecting down from the upper side of the slot is a rib, *e*, provided with a triangular-shaped stop, *f*, and also with a notch, *g*, the two being formed and arranged in manner as represented.

The key-holes of the case are shown at *h i*.

Figure 5 exhibits a top view, and

Figure 6, a rear elevation of the bolt.

Figure 7 is a rear-end view of it.

A spring-catch, *k*, formed as shown in top view in Figure 8, projects from the rear end of the lock-case, and bears against the stop *f*, and serves with such stop to hold the bolt in its advance, as well as in its rearmost position.

A lever or tumbler, *l*, pivoted to the bolt by a pin, *m*, projecting therefrom, has its longer arm extended into a passage, *o*, which goes through a ward-case, *C*, encompassing a rotary key-receiver, *D*.

The said longer arm is also provided with a hook or catch, *x*, to latch upon the ward-block.

The rib *e* also extends into the passage *o*.

The ward-block or case *C* is formed in two separate parts, *p q*, one of which is attached to the lock-case and the other to the cap, and within them is a cylindrical chamber, *r*, provided at its opposite ends with the key-holes *h i*.

The chamber is concentric with the key-receiver *D*, which is a cylinder pivoted at its opposite ends in the ends of the chamber, and provided with grooves, *s s*, running lengthwise through its opposite sides, such grooves being to receive the prongs *t t* of the bifurcated key, which is made of thin plate-steel, and has a side view, as shown in fig. 4, in which each of the prongs is shown as provided with a series of notches, *u*.

Projecting from the inner curved surface of the

ward-block is a series of annular wards or ring-sections, *v v v*, which enter the notches *u* of the prongs of the key, while the key is in the act of being revolved.

These wards and notches are for safety, and to prevent any other key whose notches may not be arranged in correspondence with the wards from being used in the lock.

When the key is in the key-receiver, and is being revolved for the purpose of throwing the bolt, such key will act directly against the side of the key-notch *g* in the bolt.

In throwing back the bolt, the key also first acts against the tumbler and raises it out of enlatchment with the ward-block, for when the bolt is advanced to its extreme position, the tumbler latches on the front of the ward-block, so as to hold the bolt in its forward position.

On the front arm of the tumbler being raised by the key, the rear arm of such tumbler will be borne down upon the spring-catch *k*, so as to depress it, and thereby facilitate the retreat of the bolt.

Within the lock-case is a small bolt, *y*, provided with a spring, *z*, for advancing it.

This bolt passes into the ward-block, and enters one of the grooves of the key-receiver *D*, and serves to hold it stationary while the key is out of it, the same being to hold the grooves of the receiver in their proper position, with respect to the key-holes, to enable the key, after having been inserted in either hole, to enter the receiver.

While passing into the receiver, the bevel *a'* of one of the prongs of the key will be pushed against the end of the bolt *y*, and will force the said bolt back out of the receiver, so as to enable the receiver to revolve with the key, and preserve such key in its due relation with the wards.

In a patent, 84,484, granted December 1, 1863, on an invention made by me, such being an improvement in mortise-locks, the case, the bolt, and the spring-catch, were substantially like those hereinbefore described.

In such lock, there was also a lever like the tumbler *l* hereinbefore mentioned, its purpose being simply to act against and move the spring-catch *k* of the cam-stop *f*.

In my present lock, the lever or tumbler *l* performs the function of so operating the spring-catch; but, besides this, it is formed on its front end as a latch or hook to catch on the ward-case and hold the bolt forward.

I, therefore, herein make no claim to the combination and arrangement of the lever *l* with the cam-stop *f*, the spring-catch *k*, and the slotted bolt and its case; nor do I claim the combination of a catch-tumbler and stud with a bolt and case, the said catch-tumbler being to hold the bolt in an advanced state,

and to be moved off the stud by the key preparatory to the bolt being thrown back by the key, such being common in many locks. 1. I claim the combination of the lever *l*, cam-stop *f*, the spring-catch *k*, and the slotted bolt and cylindrical case, as described with a latch-head or hook, *x*, on the front of such lever, and with a ward-block or stud for the hook to catch upon, such ward-block or stud being projected from the case. 2. I also claim the ward-block or case, as con-

structed in two separate parts, *p* *q*, and having one of such parts attached to the cover, and the other to the case of the lock.

3. I also claim the ward-block, as made with the annular wards and the bolt-rib passage *o* going through it, as set forth.

M. B. FOOTE.
